UNITED STATES PATENT OFFICE.

ARTHUR PRESCOTT BARKER, OF LYNN, MASSACHUSETTS.

FUEL NOZZLE FOR CARBURETORS.

Application filed February 26, 1923. Serial No. 621,175.

To all whom it may concern:

Be it known that ARTHUR PRESCOTT BARKER, citizen of the United States of America, residing at Lynn, in the county of Essex and Commonwealth of Massachusetts, has invented certain new and useful Improvements in Fuel Nozzles for Carburetors, of which the following is such a full, clear, and exact description as will enable others versed in the art to which it appertains to make and use the same.

My invention relates to the fuel nozzles of carburetors intended for use with internal combustion engines. It embodies the combinations constructions and arrangements herein set forth and claimed.

The objects of my invention are to eliminate screens and other clogable devices heretofore resorted to for fuel mixing; to insure a more perfect fuel combustion than has heretofore been had; to largely eliminate carbon; to insure maximum power from minimum fuel consumption, and to achieve the vaporization of a volatile fuel through atomization, thereby increasing the exposed surface of the fuel and facilitating vaporization, by then dispersing these atomized particles throughout incoming air currents, thus furnishing a thorough and uniform mixture capable of complete combustion.

I accomplish the objects of my invention as shown in the accompanying drawings, which form a part of this specification, and in which—

Figure 1 shows my device attached to an internal combustion engine.

Figure 2 shows the detail of my improved nozzle.

Referring again to Figure 1, A shows the intake of the internal combustion engine pictured. B shows a piston, D shows my improved spray nozzle in its intended position, E shows the carburetor, M shows the air intake. In Figure 2, C shows the passage through the center of the nozzle D, F shows the bell mouth at the end of the passage C, G shows the cuts in the bell mouth, H shows the inclined faces on said cuts, J shows the projections extending from the inclined faces H, K shows a series of horizontal grooves which cross the vertical grooves L.

Those familiar with the art to which my invention appertains will understand that as the air pressure is reduced in the air passage A (Fig. 1) by the suction stroke of a

piston B of the engine, a stream of liquid fuel is forced thru the passage C of the nozzle D by the pressure of the air in the float chamber E. The liquid stream spreads out at the cuts G in the bell mouth, contacting with and following the inclined faces H, thru force of adhesion. Each of the liquid fuel stream divisions, following the respective inclined faces H at the instant of projection from the nozzle, is subdivided by contact with a projection J extending from the inclined face H into the bell mouth F, thus subdividing the stream of liquid fuel and preparing it for mixing with the air then rushing up the exterior grooves L. As the onrushing air strikes the stream of liquid fuel at points where the adhesive force has most effectively weakened its cohesion, a maximum disruption of the fuel is had before and as it leaves the nozzle. That portion of the air from the intake M rushing up the vertical grooves L has a free and direct flow. That part passing over the horizontal grooves K is retarded. A certain quantity of air passes from the horizontal to the vertical grooves thus forming minute vortices. These vortices or whirling air currents act as a powerful means for picking up, tearing apart, scattering, vaporizing and mixing the liquid fuel stream against which they are projected.

The foregoing is a description of the effect of the nozzle upon the air currents, the liquid fuel, and their interaction prior to reaching the tip of the nozzle. After the air currents, rushing by the horizontal grooves K, pass the tip of the nozzle they converge, by reason of the curvature of the restricted orifice above the nozzle toward its center forming a sort of dome. The air rushing up the vertical grooves L, picks up the fuel as above described, projects it against and into this air dome, where the interacting and co-acting currents produce complete atomization. The atomized fuel is then dispersed throughout the intake tube. The liquid fuel stream is thus projected into violently agitated air currents before, at the time of and after leaving the nozzle, resulting in its complete disruption and vaporization. The complete combustion of the resulting mixture is thus rendered possible.

Having thus described my invention I claim as new and desire to secure by Letters Patent of the United States,

1. A fuel nozzle for carburetors presenting a bell mouth and grooved to provide a series of exterior vertical grooves extending into the bell mouth and a series of horizontal grooves extending between the vertical grooves. 20
5. A fuel nozzle for carburetors having a fuel passage terminating in a bell mouth and being grooved exteriorly to provide a series of intersecting and co-acting vertical and horizontal grooves for retarding and vorticing respective portions of passing air, 25
10. the said vertical grooves terminating in and entering the said bell mouth in such manner as to divide the same into relatively spaced apart members, and a fuel atomizing projection carried by each member and projecting into the said fuel passage. 30
15. 2. A fuel nozzle for carburetors presenting a fuel orifice, and fuel atomizing prongs formed by parts of the nozzle projecting into the orifice.
3. A fuel nozzle for carburetors presenting a fuel passage terminating at one end in a bell mouth having sections of its wall prolonged to form a serrated edge.
4. A fuel nozzle for carburetors presenting a fuel passage terminating at one end in a bell mouth formed of a series of peaks, said peaks terminating in prongs which extend into the said mouth.
